(57) **CLAIM**

The ornamental design for a removable smoker lid, as shown and described.

DESCRIPTION

FIG. 1 is a top perspective view of a removable smoker lid, showing my new design in its environment of use;

FIG. 2 is a left side elevation view showing the design removed from the environment;

FIG. 3 is a right side elevation view thereof;

FIG. 4 is a bottom view thereof;

FIG. 5 is a top plan view thereof;

FIG. 6 is a front elevation view thereof;

FIG. 7 is a rear elevation view thereof;

FIG. 8 is a top perspective view thereof; and,

FIG. 9 is a bottom perspective view thereof.

The broken lines in FIG. 1 depict environmental subject matter and form no part of the claimed design.
